(74) Attorney, Agent, or Firm—Vierra Magen Marcus & DeNiro LLP

(57) **CLAIM**

The ornamental design for a memory card, as shown and described.

DESCRIPTION

FIG. 1 is a top perspective view of a memory card, on a slightly reduced scale;

FIG. 2 is a bottom perspective view thereof, on a slightly reduced scale;

FIG. 3 is a top view thereof;

FIG. 4 is a bottom view thereof;

FIG. 5 is a first side view thereof;

FIG. 6 is a second side view thereof;

FIG. 7 is a front view thereof; and,

FIG. 8 is a rear view thereof.

The broken line drawings of pins in FIGS. 2 and 4 are for illustrative purposes only and form no part of the claimed design.

1 Claim, 1 Drawing Sheet
